United States Patent Office

Des. 178,632

Patented Sept. 4, 1956

178,632

BALL POINT PEN OR SIMILAR ARTICLE

Parker Z. Bioser, Columbus, Ohio, assignor to The Zaner-Bloser Company, Columbus, Ohio, a corporation of Ohio

Application September 14, 1954, Serial No. 32,271

Term of patent 14 years

(Cl. D74—17)

FIG. 1

FIG. 2

Figure 1 is a perspective view of a ball point pen or similar article constructed according to my new design.

Figure 2 is a sectional view taken along line 2—2 of Figure 1.

I claim:

The ornamental design for a ball point pen or similar article, as shown.
